UNITED STATES PATENT OFFICE.

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS.

PENCIL.

Application filed August 4, 1926. Serial No. 126,978.

This invention relates to a pencil having a hollow body through which a lead may be fed into position for writing, and more particularly to certain means for advancing the lead, as desired. It is directed also to an improved process of forming one of the propelling components of the pencil, and to greater simplicity in its construction and operation.

10 In the accompanying drawings is shown an exemplification of my invention in the manner following:

Figure 1 is a longitudinal section taken centrally through the pencil;

15 Figs. 2 and 3 are enlarged transverse sections therethrough taken, respectively, on lines 2-2 and 3-3 of Fig. 1;

Fig. 4 is an enlarged fragmentary detail in section of the upper end of the pencil tip and associated parts;

20 Figs. 5, 6, 7 and 8 are longitudinal sections showing four stages in the development of the tip by a die-forming process;

Fig. 9 is a longitudinal section through 25 the lower pencil end showing a tip of slightly modified construction;

Fig. 10 is a fragmentary detail in elevation of the tip appearing in Fig. 9; and

Fig. 11 is a fragmentary detail in section, 30 similar to Fig. 4, showing a modification in the neck of the tip.

The present pencil may comprise a body A having at one end a rotatable tip B and at the opposite end a ferrule C wherein is retained an eraser by any suitable means. In the upper portion of the pencil body is a chamber 11 forming a magazine for reserve leads and closed at its bottom as by a partition 12. Extending below this partition is 35 an elliptical chamber having, by preference, a tubular lining 14 fitted closely against the walls thereof. This latter chamber terminates adjacent a flaring shoulder 15 below which is a circular bore 16 extending to the bottom end of the pencil. Within this lower bore is preferably fitted a circular lining 17 which terminates flush with the lower pencil end. It may also be desirable to provide, as shown, an annular recess adjacent the lower 40 pencil end upon the outer side thereof.

A pencil body so constructed is adapted to co-operate with a tip B which, in the form shown, comprises a conical wall 18 straightened as at 19 for a portion of its length, and then doubly reversely bent in an inward di-

rection as at 20 and 21 from which latter point it continues upwardly to provide a neck 22. At its upper end the neck may be inwardly bent at 23 to provide a constricted throat 24 wherein are formed screw threads 60 25. A tip having these general characteristics is shown also in Figs. 9 and 10, differing therefrom only in that the reverse bends are omitted, an inclined shoulder 26 being substituted therefor. Such a shoulder is 65 adapted to seat against the lower end of a pencil which is inwardly beveled as at 27, after the manner illustrated in Fig. 9.

With a tip of the character described I associate a tube 28 which is extended axially 70 within the tip for the greater portion of its length. The lower end of the tube is rested against the tapering walls of the tip, and its upper end, by preference, is outwardly flared as at 29 to rest against the neck 22 at the 75 juncture of the inward bend 23. The tube is thus secured within the tip with sufficient firmness for all needful purposes. A modification of this construction appears in Fig. 11 wherein the upper tube end is offset outwardly at 29^a to bear against the neck walls which are bent over and downwardly to form a threaded throat 24^a which lies inwardly of the offset tube end. If desired, a split ring or washer 30 may be positioned between the 80 tube and neck near the lower end of the latter, whereby to lend additional support to the former. In lieu of the tube just described, it is possible with equal advantage to make use of a spiral 31 which extends 85 axially within the tip. If the spiral be placed under slight endwise compression, a firm and steady mounting within the tip is assured.

The tube 28 (or spiral 31) serves as a 90 guide for a lead D which is adapted to be fed through the lower extremity of the tip. Its travel is effected by means of a threaded propeller 32 having a flattened head 33 adapted to slide freely within the elliptical 95 lining 14 wherein it is incapable of turning. The threads of this propeller extend from below a smooth portion 34 adjacent its head throughout most of its length, and co-operate with the threads 25 in the throat 24 100 of the tip. The lower end of the propeller which may be unthreaded is preferably tapered slightly as at 35.

A pencil answering generally to this description may be produced very economi- 110

cally. Its body is preferably formed of some material which can be moulded and pressed to the desired shape around the linings 14 and 16 which are thereby permanently anchored in place. A similar lining 36 may also be provided for the chamber 11 as shown. The remaining parts of the pencil, excepting only the propeller, may be conveniently formed from tubing by a novel process which I will now explain.

In Fig. 5 I have shown a short length of tubing which is suitable for the production of the tip B. It is first drawn to the form of Fig. 6 so as to provide a taper throughout its lower portion. If desired, one or more slits 41 may be formed at its lower extremity, in accordance with common practice, so as to produce spring sections which frictionally engage the lead. The upper end 20 of the tube is then subjected to the action of dies which produce the reverse bends 20 and 21, and reduce the upper end to form the neck 22, as shown in Fig. 7. Before finishing the tip, the tube 28 (or spiral 31) is dropped in place, also the ring 30, which is preferably slit, so as to stay in place by its own spring action. The final operation of forming the throat 24 is then proceeded with. By these successive steps a tip answering to the preceding description may be produced expeditiously and economically.

The operation of the pencil should be readily understood. The neck of the tip is fitted within the lining 16 and because of the resulting metal to metal contact I obtain a frictional connection which permits the tip to rotate smoothly relative to the body of the pencil. In Fig. 3 I have suggested a cross sectional form of the neck which provides a plurality of spring sections 42 for engaging the lining 16. These may be formed conveniently by pressing inwardly the intervening neck portions 43, as shown, whereby to produce a plurality of bulging surfaces. The upper tip edge formed by the reverse bend 20 provides in effect a collar adapted to fit into the annular recess surrounding the lower body end, whereby to form therewith a neat connection. To the inside of this recess the body wall is relatively thin but on account of the reinforcement derived from the lining 16 it is adequately strong for all purposes. This manner of uniting the tip to the lower end of the pencil makes for a very efficient and serviceable construction, such that the one part reinforces the other. In the construction shown in Fig. 9, the inwardly beveled surface 27 co-operates with the inclined shoulder 26 in such a manner that a centering action takes place irrespective of the fit of the neck 22 within the lining 16.

By rotating the tip relative to the body, the propeller which cannot turn within the latter, is moved lengthwise due to the feed-

ing action of the screw threads 25 upon the threads of the propeller. This movement will continue until the threaded surface of the propeller has traveled past the throat 24. At this point (see Fig. 9) the threads 25 (preferably rolled so as to project into the throat 24) when engaged with the smooth surface 34 cannot further advance the propeller, even though rotation of the tip continues relative to the body. By this means I eliminate the possibility of binding or jamming of the parts when the propeller has reached the limit of its travel.

Referring again to Fig. 9, it will be noted that the lower tapered end of the propeller is projected into the opening at the lower tip end. On account of the tapered walls which are presented to each other, the propeller has a tendency to reverse its movement whenever permitted so to do. I take advantage of this so as to effect a re-engagement of the threads 25 with those on the propeller without having to apply thereto any extraneous pressure.

I claim:

1. A pencil having a body, a tapered tip member fitted rotatably to the lower end of the body, a guide tube extended longitudinally within the tip member, said tip member being swaged inwardly adjacent its upper end and internally threaded to provide a threaded throat confining the upper end of the guide tube the lower end of which is rested against the tapered tip walls, and a screw propeller coacting with the threads in the throat and having a head which is fitted slidably but non-rotatably within the body, substantially as described.

2. A pencil having a body with an external annular recess at its lower end, a tip member formed in its lower region with tapering walls which straighten up to provide a collar which surrounds the recess extending around the body, the tip member being further formed with a double reverse bend immediately adjacent the collar whereby to provide a neck of reduced diameter adapted to extend within the body for an appreciable distance, a lead guide tube enclosed within the tip member and supported thereby at its opposite ends, a threaded throat swaged over said tube at the upper end of the neck providing a bar against removal of the tube, a threaded propeller adapted to coact with the throat to advance within the tip member, and means within the pencil body co-acting with the propeller to permit the same to slide freely but non-rotatably therethrough, substantially as described.

3. A pencil comprising in combination a body, means therein providing a non-circular axial opening, a removable tip member having a circular resilient portion adapted for frictional rotatable connection with the

- lower end of the body, a lead guide tube mounted within the tip member, the tip member being swaged inwardly at a point beyond one end of said tube and internally threaded, and a propeller adapted for travel through the tube and having threads which engage with those on the tip member, the propeller being provided with a head which cooperates with the non-circular portion of the axial opening, substantially as described.
4. A pencil having a body with a non-circular axial opening, a tip member detachably connected to the body for rotation relative therewith, a propeller movable longitudinally through the body opening into the tip member, there being means for preventing rotation of the propeller relative to the body, and interengaging screw threads on the tip member and propeller terminating on the latter short of its upper end whereby to advance the propeller through a limited distance only in response to continued rotation of the tip member relative to the body, substantially as described.
5. A pencil having a body to which is fitted a rotatable tapered tip member having internal threads, a propeller having both smooth and threaded surfaces, the latter co-acting with the tip member, and means by which rotation of the propeller relative to the body is prevented, the propeller being movable through the tip member in response to rotation thereof relative to the body, the smooth portion of the propeller surface receiving engagement from the tip member threads at one point in its movement whereby further advance of the propeller is checked, substantially as described.
6. A pencil having a body to which is fitted a rotatable tapered tip member having internal threads, a propeller having both smooth and threaded surfaces, the latter co-acting with the tip member, and means by which rotation of the propeller relative to the body is prevented, the propeller being movable through the tip member in response to rotation thereof relative to the body, the smooth portion of the propeller surface receiving engagement from the tip member threads at one point in its movement whereby further advance of the propeller is checked, and the propeller end being tapered to receive pressure from the tapered walls of the tip member when the propeller movement is arrested whereby the propeller is urged reversely preliminary to a reverse rotation of the tip member relative to the body, substantially as described.
7. A pencil having a body to which is rotatably connected a tapered tip member one end of which is internally threaded, a propeller threaded to co-act with the tip member except in the region of its two ends the forward of which is tapered to receive pressure from the tip member walls when advanced to the limit of its movement, the opposite propeller end in such position lying adjacent the tip member threads whereby further co-action therewith is arrested, and means for preventing rotation of the propeller relative to the body while permitting free sliding movement longitudinally thereof, substantially as described.
8. A pencil having a body to which is rotatably connected a tip member having tapered walls at its lower end, a tube axially mounted within the tip member having its upper end outwardly flared and its lower end bearing against the tapered walls of the tip member, the upper end of the tip member being reduced to form a neck which surrounds the tube in spaced relation except at its flared upper end, the upper end of the neck being swaged inwardly and threaded to provide a threaded throat at the extremity of the neck providing means for retaining the tube within the tip member, and a threaded propeller co-acting with the threaded throat having means for resisting rotation relative to the body when the tip member is rotated relative thereto, substantially as described.
9. A pencil having a body to which is rotatably connected a removable tip member wherein is mounted an axial tube supported therein at its upper and lower ends, the tip member being extended upwardly beyond the tube at which point the tip member is swaged inwardly and provided with internal threads, and a threaded propeller coacting with the tip member and slidably mounted within the body but non-rotatable therein and adapted for travel through the axial tube in response to rotation of the tip member relative to the body, substantially as described.
10. A pencil having a body to which is rotatably connected a tip member wherein is mounted a lead guiding means supported at its upper and lower ends, the tip member being extended upwardly beyond the tube at which point the tip member is swaged inwardly and provided with internal threads, a threaded propeller coacting with the tip member slidably mounted within the body but non-rotatable therein and adapted for travel through the axial tube in response to rotation of the tip member relative to the body, substantially as described.

JOHN P. LYNN.
